UNITED STATES PATENT OFFICE.

CHARLES H. WEBSTER AND WILLIAM G. WEBSTER, OF BUFFALO, N. Y.

STOCK-CAR.

SPECIFICATION forming part of Letters Patent No. 228,499, dated June 8, 1880.

Application filed May 4, 1880. (No model.)

To all whom it may concern:

Be it known that we, CHARLES H. WEBSTER and WILLIAM G. WEBSTER, both of the city of Buffalo, in the county of Erie and State of New York, have invented certain new and useful Improvements in Stock-Cars, which improvements are fully set forth in the following specification and accompanying drawings, in which—

10 Figure 1 is a side elevation of a stock-car having our invention combined therewith. Fig. 2 represents a vertical longitudinal section through the center of the car. Fig. 3 is a front view of one form of one of the separating-bars or stall-frames; Fig. 4, a side view of one of the movable bars; and Fig. 5 represents a top view of a fragment of a car, showing a folding door, partly opened, and the arrangement of the hinges thereon, and Fig. 6 is a stall-frame.

20 The object of the first part of our invention is to provide the means for readily changing from a single to a double deck car, so as to allow the same car to be used for large stock or easily adjusted for the purpose of loading 25 small stock—such as sheep, hogs, &c.; also, to permit the unloading of small stock from the level of the platform by lowering the upper deck.

The object of the second part of our invention is to provide the means for readily throwing open the whole side of the car when required, as will be more clearly hereinafter shown by reference to the drawings, in which—

30 A represents the car; B, the doors, of which there are two on each side, arranged to open and fold together, as shown in Fig. 5, the letters C representing the hinges. D D are two bars, arranged two on each side of the car and 40 joined to the doors at E E. When opening the doors the ends of the bars are lifted out of the catch F and turned up vertically, or nearly so, substantially as shown by dotted lines F' F'.

G represents the adjustable or movable deck. G' is a screw arranged to work in a nut in the lower deck and to project up through the upper or movable one. It is provided with a flange (shown at G², Fig. 2) and a square

head, G³, so that it can be turned with a wrench, and thereby raise or lower the deck. 50

We do not confine ourselves to the precise arrangement shown, as two or more removable screws similar to those shown at H, Fig. 2, may be used.

I represents a number of bars, jointed to the 55 deck at I', for holding it firmly in position when elevated. When it is necessary to lower the deck it is first raised high enough to loosen the bars I, which are then folded up under it, as shown at J, Fig. 2, and the deck is then lowered down, so as to form a single-deck car.

It will be readily seen that removable bars may be used instead of the bars I, or that bolts may be arranged in the sides of the car, which can be forced into the sides or under the deck, 65 and thereby hold it up.

The division or stall frames for forming the separate stalls may be arranged as shown in Fig. 2 and in the reduced drawing, Fig. 6.

The letters K represent the frame-bars, and 70 L the cords for holding them together. They are fastened to the lower bar and allowed to slip easily through the upper bar. Both cords are joined together at the top and are arranged to be let down or drawn up by means 75 of the windlass M, (shown in Fig. 2,) which is operated by any well-known means for the purpose. These frames are constructed so as to move easily up or down in the grooved bars N, which are made adjustable lengthwise of 80 the car, so as to vary the width of the stalls.

In Fig. 3 we have shown an equivalent arrangement of stall-frame, which is also adjustable lengthwise of the car, as shown in Fig. 2. 85

The object in drawing up the stall-frames is to get them out of the way when the car is used as a double-deck car or when unloading the stock, and thereby allow a free exit to the animals by giving them a better chance to come 90 together or turn around when necessary. The door-bars P are also made adjustable lengthwise of the car, so that if, in adjusting the stalls, one should come in the way, it can be moved to one side until the animal has entered the 95 stall.

We claim as our invention—

1. In a stock-car, an adjustable deck, G, provided with bars I, jointed thereto at I', and adapted to be folded, as specified, in combination with one or more screws, G', arranged to operate in nuts in the lower deck, and provided with a flange, G², as and for the purposes described.

2. The folding doors B, hinged at C C C, as

specified, in combination with the bars D and 10 fastening F, substantially as and for the purposes shown.

CHARLES H. WEBSTER.
